PNEUMATIC HAMMER TESTING MACHINE

Hugo V. Cordiano, Joseph J. De Paolo, and
Hyman Lacks, New York, N. Y.

Application May 11, 1945, Serial No. 593,176

4 Claims. (Cl. 73—11)

(Granted under the act of March 3, 1883, as
amended April 30, 1928; 370 O. G. 757)

This invention relates to a machine for testing pneumatic hammers, particularly pneumatic chipping hammers.

Accurate measurement of the relative performance of pneumatic chipping hammers offers many difficulties. In manual operation, for example, it is extremely difficult to make a cut of uniform thickness, to maintain uniform feed pressure on the chipping hammer, and to maintain a constant angular relationship between the cutter or chisel of the hammer and the work. Because of these difficulties and the variables introduced, estimation of the relative performance of various chipping hammers through manual operation is of little value.

An object of this invention is to provide a machine for testing pneumatic chipping hammers in which the thickness of cut made by the hammer chisel may be predetermined and kept constant.

Another object of this invention is to provide a machine for testing pneumatic chipping hammers in which the feed pressure acting upon the hammer may be maintained at a constant and predetermined value.

Still another object of this invention is to provide a machine for testing pneumatic chipping hammers in which the angle of the hammer and its chisel with respect to the work may be maintained at a constant and predetermined value.

Further objects and advantages of this invention, as well as its construction, arrangement and operation, will be apparent from the following description and claims in connection with the accompanying drawings, in which,

Figure 1 is a side elevation of the machine of this invention.

Figure 2 is a top plan view of the machine of Figure 1.

Figure 3 is a partial section of the machine of this invention, taken along the line 3—3 of Figure 1.

Figure 4 is a partial section of the machine of this invention, taken along the line 4—4 of Figure 2.

Figure 5 is an enlarged side elevation of the intermediate cutter piece of the machine.

Figure 6 is an enlarged side elevation of the cutter of the machine, and

Figure 7 is an enlarged bottom plan view of the cutter of the machine.

Referring to the drawings in detail, the framework of the machine comprises two upright members or channels 11, welded or otherwise rigidly

secured to a heavy base plate 12. Suitably affixed to the tops of channels 11 are two parallel, spaced angles or cover plates 13. Rigidly mounted on the upper surfaces of cover plates 13 are two parallel spaced guideways or tracks 14. Carriage 15 rests upon tracks 14, and is slidably engaged with the outer flanges thereof (Figure 4). Yoke 16, slidably mounted on carriage 15, is adapted to engage and hold the forward inner surface of the handle of pneumatic hammer 17. Yoke 16 is provided with two drilled holes through which extend threaded rods 18, which are anchored at their forward ends in carriage 15. In threaded engagement with each of the rods 18 are two nuts 19, one on either side of yoke 16, by means of which yoke 16 may be adjusted relative to carriage 15 and locked at any desired point of adjustment. Bolts 20 extend through slots 21 in yoke 16, engaging threaded bolt holes 22 in carriage 15 (Figure 2). Several pairs of bolt holes 22 are provided in carriage 15, being so spaced that in any position of yoke 16 relative to carriage 15, bolts 20 extending through slots 21 may engage at least one pair of bolt holes 22. Bolts 20, through the medium of washers 23, clamp yoke 16 firmly against carriage 15 at any selected position, preventing vibration of yoke 16 relative to carriage 15. Flexible line 24 is the means by which air is delivered to pneumatic hammer 17 under pressure.

Extending from and impelled by pneumatic hammer 17, and extending through a guide hole in carriage 15, is a square ended chisel blank 25. Chisel blank 25 acts upon and impels a raised portion of the intermediate cutter piece 26 (Figure 5), which acts upon and impels cutter 27 (Figures 6 and 7). Intermediate cutter piece 26 and cutter 27 are retained and guided by the inner flanges of tracks 14 (Figure 4).

Brackets 28 extend from the upper end of the forward channel 11, and support pulley 29, preferably mounted in antifriction bearings. Stud 30 projects from the forward end of carriage 15. Cable 31, connected to stud 30 by clevis 32, rides on pulley 29 and supports weights 33. Stop 34, of plastic or other suitable material, limits the travel of cutter 27 and retains it in tracks 14.

Suitably affixed to the web of the forward channel 11, as by bolting or welding, is a pair of spaced guides 35 (Figure 3). Rear guides 36, parallel to guides 35 and similarly spaced, extend from base plate 12 to cover plates 13 approximately midway between channels 11, and are fixedly secured at both ends. The ends of elevator bar 37 extend between guides 35 and rear guides 36,

Handles 38 are provided on elevator bar 37 to facilitate changing its position. Guides 35 and rear guides 36 are provided with multiple equally and correspondingly spaced holes 39, by means of which elevator bar 37 may be supported in alternate horizontal positions. Elevator bar 37 is fixed at any alternate horizontal position desired by through bolts 40, each of which extends through a pair of corresponding holes 39 provided in guides 35 and rear guides 36 and through a hole provided in elevator bar 37 near its end for that purpose. As illustrated, elevator bar 37 is provided with two holes near each end, adapted to receive through bolts 40.

Slab or plate 41, the material being worked upon by pneumatic hammer 17 and cutter 27, rests upon elevator bar 37. Locking bolts 42, in threaded engagement with holes 39, may be provided to prevent sidewise movement of slab 41. Locking bolts 42 may be ordinary machine bolts provided with lock nuts, or may be set screws, wing nuts or any equivalent device, and may bear directly upon slab 41, or upon side plates (not shown) adapted to be inserted to bear on slab 41. Plates 43 may be rigidly affixed to the rear surfaces of rear guides 36, and locking bolts 44, similar to locking bolts 42, may be provided in threaded engagement therewith to hold slab 41 firmly against the web of the forward channel 11.

In operation of the invention, slab 41 is lowered into the machine between tracks 14, so that it rests upon elevator bar 37. By means of handles 38, through bolts 40 and holes 39, slab 41 and elevator bar 37 are adjusted vertically to approximately the position desired. Slab 41 is then adjusted vertically until its upper surface is substantially coplanar with the lower surfaces of tracks 14, by means of shims inserted between elevator bar 37 and slab 41. With slab 41 in the desired position, it may be secured in that position by locking bolts 42 and locking bolts 44.

Cutter 27 is then inserted between tracks 14, its cutting edge being brought up to the rear end of the top surface of slab 41, and the intermediate cutter piece 26 is inserted behind it. A pneumatic hammer 17 to be tested is rigidly fixed in carriage 15 by means of yoke 16, threaded rods 18 and bolts 19, and the assembled carriage 15, pneumatic hammer 17 and chisel blank 25 are engaged with tracks 14 and slid into place behind intermediate cutter piece 26.

A constant feed pressure for pneumatic hammer 17 is supplied by weights 33, which are attached to cable 31 and act on carriage 15 and pneumatic hammer 17 through clevis 32 and stud 30. Weights 33 must be large enough to obviate recoil of pneumatic hammer 17, 100 pounds being suitable for the usual size chipping hammer. A supply of compressed air is conducted to pneumatic hammer 17 through flexible line 24. Pneumatic hammer 17 is then permitted to operate for a measured period of time, at the end of which period the chip produced is removed and weighed. The pressure of the air operating pneumatic hammer 17 is maintained constant throughout the period of the test, either manually or by suitable regulating means. The air consumption is measured by a direct reading air meter, a liquid displacement meter, or by any other suitable means. The data thus obtained, the weight of steel chipped per minute and the weight of steel chipped per unit of air consumed, are highly indicative of the performance and efficiency of any pneumatic hammer being tested.

Clevis 32 is provided so that the chip being

removed from slab 41 will not interfere with cable 31, thereby altering the feed pressure on carriage 15. Clevis 32 also permits chips to be removed and gathered in one piece, simplifying weighing and tagging. Stud 30 is so located that cable 31 pulls in a line which passes approximately through the center of gravity of the loaded carriage 15. The intermediate cutter piece 26 is so shaped that the center axis of the chisel blank 25 passes through the center of gravity of the intermediate cutter piece 26. Cutter 27 is separate from the intermediate cutter piece 26, so that resharpening of cutter 27 does not change the center of gravity of the intermediate cutter piece 26. The shape of the intermediate cutter piece 26 and the use of a separate cutter 27 eliminate any tendency of the cutting edge to dig in or run up, since a horizontal component of force only is transmitted to the cutter 27.

The accuracy and value of comparative results obtained by testing in the machine of this invention may be increased by keeping constant other factors than those already pointed out. The angle of pneumatic hammer 17 relative to slab 41, it will be apparent, is fixed and constantly maintained by the shape of carriage 15. The angle of the cutting edge of cutter 27 relative to slab 41 should be maintained within close limits by frequent honing and grinding. All test plates or slabs 41 should preferably be of the same size, specifications and hardness, and it has been found desirable to do all chipping in the direction of rolling. It has also been found that new, unused hammers cut progressively faster when initially tested. It is desirable, therefore, to run in new hammers by impacting against a steel block for a suitable period of time before testing in the machine of this invention.

It is to be understood that various modifications and changes may be made in this invention without departing from the spirit and scope thereof as set forth in the appended claims.

The invention described herein may be manufactured and used by or for the Government of the United States of America for governmental purposes without the payment of any royalties thereon or therefor.

What is claimed is:

1. A machine for testing pneumatic hammers comprising a guideway, means adapted to hold a test plate in fixed relationship with said guideway, means slidably retained by said guideway for holding a pneumatic hammer in fixed angular relationship with said guideway, means for applying a constant feed pressure to said pneumatic hammer holding means, and cutting means slidably retained by said guideway and adapted to receive impact forces at an angle not parallel to said guideway and to transmit said forces in a direction parallel to said guideway.

2. A machine for testing pneumatic hammers comprising a framework and a guideway thereon, means secured to said framework adapted to hold a test plate in fixed relationship with said guideway, means slidably retained by said guideway for holding a pneumatic hammer in fixed angular relationship with said guideway, means for applying a constant feed pressure to said pneumatic hammer holding means, means slidably retained by said guideway and adapted to receive impact forces at an angle not parallel to said guideway and to transmit said forces in a direction parallel to said guideway, and cutting means slidably retained by said guideway and adapted to be driven by said impact transmitting means.

3. A machine for testing pneumatic hammers comprising a framework and a pair of spaced guideways thereon, means secured to said framework adapted to hold a test plate in fixed relationship with said guideways, means slidably retained by said guideways for holding a pneumatic hammer in fixed angular relationship with said guideways, means for applying a constant feed pressure to said pneumatic hammer holding means, means slidably retained by said guideways and adapted to receive impact forces at an angle not parallel to said guideways and to transmit said forces in a direction parallel to said guideways, and a cutter slidably retained by said guideways adapted to be driven by said impact transmitting means.

4. A machine for testing pneumatic hammers comprising a framework and a pair of spaced guideways thereon, means secured to said framework adapted to hold a test plate in fixed rela-

10
